[57] CLAIM

The ornamental design for an apron, substantially as shown and described.

DESCRIPTION

FIG. 1 is a front elevational view of an apron showing my new design;

FIG. 2 is a rear elevational view;

FIG. 3 is a front elevational view thereof with the top of the apron dropped down and the portion of the helmet which would be seen omitted for convenience of illustration;

FIG. 4 is a view like FIG. 3 of a modified form of the apron wherein the hand signal inside the circle is replaced with the arm signal shown;

FIG. 5 is a view like FIG. 3 of a second modified form of the apron wherein the arm signal shown replaces the signals previously shown inside the circle; and

FIG. 6 is a view like FIG. 3 of a third modified form of the apron wherein the arm signal shown replaces the signals previously shown inside the circle.
